UNITED STATES PATENT OFFICE.

JOHN A. FORBES, OF DOVER, DELAWARE.

COMBINED HOE AND CULTIVATOR.

SPECIFICATION forming part of Letters Patent No. 245,619, dated August 16, 1881.

Application filed April 23, 1881. (No model.)

To all whom it may concern:

Be it known that I, JOHN A. FORBES, a citizen of the United States, residing at Dover, in the county of Kent and State of Delaware, 5 have invented a new and valuable Improvement in Combined Hoe and Cultivator; and I do hereby declare that the following is a full, clear, and exact description of the construction and operation of the same, reference being had 10 to the annexed drawings, making a part of this specification, and to the letters and figures of reference marked thereon.

Figure 1 of the drawings is a representation of a side view of the device. Fig. 2 is a plan view. Fig. 3 is a transverse section through the handles, showing the rear of the shovels.

This invention relates to hoes and cultivators; and it consists in the improved features of construction and combination hereinafter 20 fully described, and particularly pointed out in the claim.

In the accompanying drawings, the letters A A designate the handle-pieces or sides of the frame of this implement, which extend forward 25 to receive the journals or journal-boxes of the central gage and guide wheel B. The front ends of these side bars are connected by the bow-shaped clevis-bar C, which is provided with a series of perforations, a, for the attachment 30 of the draft. The side bars, A, are bolted to the ends of the bar C, and are designed to be connected in rear by means of the transverse bolt-rod D, which is provided with a nut and washers, and is designed to be easily removed and replaced. Upon this rod are arranged the perforated sections b, forming the 35 bracing-blocks between the side bars.

E E represent the standards, which are slotted longitudinally at e, near their upper ends, 40 to receive the bolt-rod D, and the handles are thereby rendered adjustable according to the depth of work required of the hoes and cultivator-shovels. These standards are also adjustable toward and from each other on the bolt-rod D, the sections b being shifted according to the space between the standards required. At their lower ends the standards are adjusted 45 toward or from each other by means of the screw-rod F and the inner and outer check-nuts, d.

To the outside of each standard are bolted

the shanks g of the hoes G G'. One of these hoes, G, extends forward from the shank and downward and outward by its curved arm H, from the lower end of which the blade h extends horizontally inward and rearward. The opposite hoe, G', has its arm H' extending rearward from the shank portion, downward, and outward, and the blade extends from the lower end of said arm inward and rearward toward the end of the opposite hoe, but in rear thereof, this arrangement being effected without increasing the rearward inclination of this blade by means of the angular relation of the arms H H' to the shank portions g. The angular 65 points k of these hoes are somewhat acute, as the blades are horizontal and the arms rearwardly inclined, as shown in the drawings. In the construction illustrated the screw-rod F serves to assist in fastening the hoe-shanks to 70 the standard, and also receives the rear ends or eyes l of the braces m, which extend to the forward ends of the side bars.

To the rear surfaces of the standards are bolted the shanks s of the cultivator-teeth or 75 shovel-carrying beams S, formed with inner and lateral branches, as shown in the drawings. These shovel-beams extend well to the rear from their shank portions, and are so arranged that their shovels follow at a little distance 80 behind the respective hoes. The points of the shovels are adjusted lower than the cutting-edges of the hoes.

It will be seen that the hoes can be adjusted to run very close to a row of plants, cutting 85 off the weeds and leaving the ground level behind. The cultivator-teeth, following, work the ground immediately afterward. In this manner much time is saved, as the cultivating and weeding is effected in once going over the 90 ground, and the result is quite perfect and satisfactory. The height of the handles is easily adjusted to suit the operator and the work, and any change required in the width between the standards can be readily effected. The wheel 95 is of good size and serves to hold up the front of the implement and to steady its movement, keeping the hoes from being forced sidewise when they encounter large weeds. In combination with the slotted standards and handles, 100 the wheel also serves to regulate the depth of action in the soil of the hoes and cultivator.

teeth. As these parts are detachable from the standards, either hoes or cultivator attachments can be used separately when it may be required for special purposes.

5 I am aware that some of the elements herein shown and described have been approximated prior to my invention, and I claim protection only for the limited construction hereinafter specifically pointed out.

10 Having described this invention, what I claim, and desire to secure by Letters Patent, is—

In a horse hoe and cultivator, the combination, with vertically and laterally adjustable

standards E E, of the opposite lateral hoes, G 15 G', secured by their shanks *g* to the outer sides of said standards, and the cultivator attachments S S, secured by their vertical shanks *s* *s* to the rear edges of said standards, substantially as and for the purposes set forth. 20

In testimony that I claim the above I have hereunto subscribed my name in the presence of two witnesses.

JOHN ALEXANDER FORBES.
